FLASHER AND SIGNAL SYSTEM

Joseph Bell, Cincinnati, Ohio

Application November 15, 1939, Serial No. 304,500

7 Claims. (Cl. 200—113)

This invention relates to an improved switching means and an automatic interrupter or flasher switch and a direction and stop signal system in which the same may be employed.

It is an object of the invention to provide a switching means including a current interrupter of a simple and improved construction.

It is also an object of the invention to provide such a switching means in a signal system for vehicles to control the supply of an intermittent flow of current to a flashing direction signal and the supply of a steady flow of current to a stop light signal.

It is a further object to provide a current interrupter or flasher switch of general application in which a resistance element in series with the switch contacts functions to automatically open and close the contacts periodically when current is supplied to the switch.

Further objects and the advantages of my present invention will appear from the following description of the embodiment illustrated in the accompanying drawings.

In the drawings:

Fig. 1 is a front elevation of the switching means.

Fig. 2 is a rear elevation of the same.

Fig. 3 is a view similar to Fig. 2 with the stationary portion of the switching means removed to show the rear face of the movable portion of the switching means.

Fig. 4 is front face view of the stationary portion of the switching means.

Fig. 5 is an enlarged transverse section taken substantially on line 5—5 of Fig. 2, showing the interrupter mechanism with its contacts in closed position.

Fig. 6 is a fragmentary diagrammatic view of the interrupter mechanism with its contacts in open position.

Fig. 6a is a fragmentary view of a portion of the interrupter mechanism with parts broken away.

Fig. 7 is an enlarged fragmentary view of a portion of the interrupter taken substantially on line 7—7 of Fig. 5.

Fig. 8 is a wiring diagram of the signal system with a diagrammatic showing of the switching means.

Fig. 9 shows a portion of the wiring diagram with a different switch position than Fig. 8.

Referring first to the wiring diagram and diagrammatic showing of the switching means in Figs. 8 and 9, the reference characters A and A' designate suitable direction signal lights which

are preferably located adjacent the rear and opposite sides of the vehicle and are also employed as stop signals operated in conjunction with the vehicle braking means. The usual car battery B supplies current to such lights through circuits which include a direction switch D, a stop light switch S, and an interrupter or flasher switch F. The reference character P designates a pilot light which is provided to indicate to the vehicle driver whether or not the direction signal is operating as desired, and the several circuits and battery are grounded as at G.

As will be more fully described hereinafter, the direction switch D is adapted to be manually operated to complete an energizing circuit from the battery through the interrupter switch F to the signal light at one side of the vehicle to indicate by a flashing signal an intended change of direction, and the stop light switch S which may be operated in the usual manner on application of the vehicle brakes is adapted to complete an energizing circuit from the battery to supply a steady current to both of the signal lights when no change of direction is intended and to supply a steady current to only one of said signal lights when the other light is being employed as a direction signal.

Proceeding now to a description of the switching means, the switch casing 10 constitutes a housing for the movable member 12 and the relatively stationary member 14 which is secured to the casing in any suitable manner such as by means of bayonet joints with slots 16 in the casing and pins 18 on the stationary member.

The movable switch member 12 is preferably formed of insulating material and is provided with a suitable socket 20 to receive the pilot light bulb P and with a cover 22 which extends outwardly through an opening in the casing 10 and is provided with a central opening 24 to permit passage of light from the pilot bulb and with a suitable operating handle 26.

On the rear face of the movable member 12 are secured the contact member 28 as by screw 30 and the contact member 32 as by screw 34. The contact member 28 is formed with spaced contact points 36 and 38 and with an inwardly extending contact arm 40 to engage the base of the pilot light bulb P, and is also provided with an inwardly extending spring contact arm 42 which is adapted to engage a centrally located contact post on the stationary member 14 to be herein-after described. The contact member 32 is formed with spaced contact points 44 and 46 and both such points and the contact points 36 and

38 of member 28 are arcuately spaced on the movable member 12 to cooperate with contacts and contact members on the stationary member 14.

The stationary member 14 is also preferably formed of insulating material and is provided on its front face with the arcuate contact members 48 and 50 and a contact 52 between the adjacent ends of such contact members as clearly shown in Fig. 4. The contact members 48 and 50 are connected respectively to the right and left signal lights and are adapted to be engaged by the contact points of members 28 and 32 on the movable member 12 to complete certain circuits to such lights as will be set forth herein-after. The contact 52 is forced outwardly into engagement with the contact member 32 on the movable member 12 by means such as spring 54 to engage either said contact member 32 or the contact points 44 or 46 thereon, and such contact 52 is connected to the battery B by a circuit which includes the stop light switch S as shown diagrammatically in Figs. 8 and 9.

The stationary switch member 14 is also provided with a central contact post 56 which is adapted to be engaged by the spring arm 42 of contact member 28 on the movable member 12 and such post 56 is connected by strap 58 on the opposite face of member 14 to the post 60 to supply current to the resistance element 62 of the interrupter or flasher switch F to be described hereinafter.

The stationary switch member 14 is further provided with a contact post 64 which is connected by strap 66 to the stationary contact 68 of the interrupter or flasher switch F with the movable contact 70 of such switch connected to the battery B, and such post 64 is adapted to be engaged by the contact points 36 and 38 to complete the direction signal circuits to either the right or left signal light as will more fully appear from the description of the operation.

The interrupter or flasher switch F is mounted as shown in Figs. 2 and 5 on the rear side of the stationary member 14 and consists generally of a spring toggle switch having the relatively fixed contact 68 and movable contact 70 and an actuating means including the resistance element 62 heretofore mentioned. The contact 68 is carried by or consists of a screw-threaded post extending through the stationary member 14 with a slotted end indicated at 72 in Fig. 4 to provide for adjustment of said contact 68 relative to the movable contact 70 which is carried by a spring member 74 riveted or otherwise secured to the L-shaped plate 76. The plate 76 has one portion extending parallel to the spring member 74 to limit movement of the contact 70 relative to such plate and also limit movement of such plate in the direction of the fixed contact, and a further portion at right angles thereto which is formed as shown in Figs. 2 and 5 with spaced knife edges 78 which engage in correspondingly spaced bearing grooves 80 in a supporting bracket 82 secured to the member 14. The securing means 84 for the bracket 82 may also serve to secure a terminal fitting 86 which is suitably connected to the battery B to supply current through the bracket 82, plate 76 and spring member 74 to the movable contact 70, and such fitting 86 is extended to function as a stop and engage and limit the pivotal movement of the plate 76 in the direction away from the fixed contact 68.

The plate 76 is maintained in pivotal engage-

ment with the bracket 82 by the tension spring 88 which is fastened at one end to the plate between and at one side of the knife edges 78 and extends a considerable distance beyond the other side of such knife edges with its opposite end connected to a movable lever 90 which is preferably formed of insulating material. One end of the lever 90 is slotted and formed with spaced arms which extend on opposite sides of the spring 88 and may engage therewith as hereinafter described, and the opposite end of the lever 90 is pivoted as at 92 within the slotted end of a screw-threaded supporting stud 94 adjustably secured to the member 14. The resistance element 62 which preferably consists of a piece of thermo-responsive wire of suitable composition to operate in the manner hereinafter described, is secured at one end to the post 60 and extends transversely to the lever 90 in engagement therewith intermediate the ends thereof and is secured at its opposite end to the post 96. A resistance coil 98 is also secured at one end to the post 96 and is in series with the element 62 for a purpose to be set forth hereinafter.

Considering first the operation of the interrupter or flasher switch F, the same has been shown in Fig. 5 with the movable contact 70 in engagement with contact 68. In such position it will be noted that the engagement of the spaced arms of the lever 90 with the spring 88 positions the intermediate portion of the spring at a point above an imaginary line through the pivot point of the lever and the point of connection of the spring to the plate 76 so that the spring exerts a tension to force the lever 90 downwardly, as viewed in Fig. 5 or in a counter-clockwise direction around pivot 92 to hold the lever in engagement with the intermediate portion of the thermo-responsive wire 62. In this position it will also be noted that an imaginary line Y between the point of connection of the spring 88 to the plate 76 and the center of the spring at the ends of the spaced arms of the lever 90 passes above the knife edges 78 forming the fulcrum of the plate 76 and the spring tension therefore also tends to rotate the plate 76 in a clockwise direction and hold the contact 70 in engagement with the contact 68.

The resistance element or thermo-responsive wire 62 is constituted of a material which becomes heated and expands when current is passed therethrough and which cools and contracts when the supply of current thereto is interrupted, and the supply of current to the wire 62 is controlled by the contacts of the interrupter dependent upon the position of the direction switch D as will be hereinafter noted. Referring again to Fig. 5 and assuming that the direction switch D has been moved to complete a circuit which includes contacts 68 and 70 and the wire 62, such wire will become heated and expand thereby permitting the lever 90 to be moved downwardly about pivot 92 by the action of spring 88 and as the intermediate portion of the spring also moves downwardly by reason of the engagement of the spaced arms of the lever 90 therewith, the imaginary line Y will move past a dead center position to a point below the fulcrum of the plate 76 and the spring tension will then rotate the plate 76 counter-clockwise and move the contact 70 quickly away from the contact 68 to the position shown diagrammatically in Fig. 6.

In the switch position shown in Fig. 6 it will be noted that the plate 76 engages the stop mem-

ber 86 and that the intermediate portion of the spring 88 is still slightly above the imaginary line through the pivot point of the lever and the point of connection of the spring to the plate 76 so that such spring is still exerting tension to hold lever 90 against the wire 62. As will be apparent, the circuit to the wire 62 has now been broken at the interrupter contacts and as the wire then cools it contracts and forces the lever 90 upwardly against the tension of the spring 88 and when the imaginary line Y moves back above dead center position the spring tension will rotate the plate 76 in a clockwise direction to again close the contacts 68 and 70 and thereby close the circuit to supply current to the wire 62. As long as one of the direction signal circuits is closed at the direction switch D, the operation just described will be repeated periodically to cause an intermittent current to flow through whatever path may be controlled jointly by the contacts 68 and 70 and the direction switch D.

Before proceeding to a description of the operation of the entire signal system, it is desired to refer to several features of the interrupter or flasher switch F which is obviously of general application and may be used with many types of signs or signals where a flashing or intermittent illumination is desired. It will first be noted that the spring 88 has, in effect, a double function. As appears from the description of the operation of the switch F, a portion of the spring 88 operates the switch plate 76 in both directions with a snap action to provide both a quick make and break of the switch contacts 68 and 70, and the spring 88 also functions to hold the lever 90 against the thermo-responsive wire 62 and move this lever upon expansion of the wire when heated in one direction. The lever 90 is moved, as has been described, in the opposite direction by the wire 62 on contraction thereof when cooling so that movement of the lever 90 in both directions to open and close contacts 68 and 70 periodically is dependent upon the current flow through the wire 62 which is controlled by such contacts.

The resistance coil 98 is provided in series with the thermo-responsive wire 62 to reduce or limit the amount of current which may pass through this wire and thereby permit the use of wire of such material as would have a longer life than if the same had to operate with full battery current or the current desired in other circuits controlled by the interrupter contacts. It will be apparent that any change in the amount of the resistance 98 will also change the rate of expansion and contraction of the wire 62 and thereby change the rate at which the lever 90 and switch plate 76 operate to open and close the interrupter contacts. The relative lengths of the open and closed periods of the interrupter contacts may be changed or adjusted both by a vertical adjustment of the pivot post 94 for the pivot 92 of the lever 90 and an adjustment of the relatively fixed contact 68.

Proceeding now to a description of the operation of the entire signal system and referring first to Fig. 8, the direction switch D is shown therein in its neutral or off position. Although in this position the contacts of interrupter switch F are closed, the circuits which include this switch are open at the direction signal switch D since there is no engagement between post 64 and either contact point of member 28, and the thermo-responsive wire 62, pilot light P and signal lights receive no current. The signal lights

A and A' may, however, be energized through the stop light circuit to provide a steady, stop signal upon closure of the stop light switch S such as on application of the vehicle brakes since the arcuate contact members 48 and 50 connected to the signal lights are engaged by the respective contact points 44 and 46 of member 32 which is engaged by contact 52 connected to the battery B by the stop light switch S.

10 When the direction signal switch D is operated to indicate a contemplated turn or change of direction, the signal light at one side of the vehicle will be disconnected from the stop light circuit and energized through a direction signal circuit to provide a flashing direction signal while the signal light at the other side of the vehicle will be retained in the stop light circuit to provide a steady stop signal if the stop light switch be closed. In the position of the switch D shown in Fig. 9 it will be seen, for instance, that current may flow from battery B through the contacts of interrupter switch F to contact post 64, contact point 36, member 28, contact point 38, arcuate member 48, to the signal light A'. From member 28, current is also supplied through contact arm 40 to the pilot light P, and through contact arm 42 to post 56, thermo-responsive wire 62 and resistance coil 98. As will be apparent the interrupter switch F will then function automatically in the manner heretofore described to periodically open and close and cause a periodic or flashing illumination of both the signal light A' and pilot light P which will continue as long as the switch D is not returned to its neutral or off position.

In the position of switch D in Fig. 9, it will also be noted that the contact point 46 has been moved out of engagement with arcuate member 48 to disconnect the signal light A' from the stop light circuit but this contact point 46 is then engaged by contact 52 and completes the circuit from the stop light switch S to the other signal light A through member 32, contact point 44 and arcuate member 50 so that such light A may be energized to display a steady stop signal on application of the vehicle brakes during the time the signal light A' is flashing to indicate a contemplated turn or change of direction towards that side on which light A' is located.

50 It will, of course, be understood that after the turn has been completed the switch D should be returned to its neutral or off position, and also that a contemplated turn or change of direction towards the opposite side should be indicated by an adjustment of switch D to provide for the flashing operation of signal light A instead of A' and disconnect such light A from the stop light circuit which may then be completed only to the signal light A'. It is not believed necessary to trace the completed circuits in this latter switch position but merely note that current would then be supplied through the interrupter switch contacts and post 64 to arcuate member 50, and in the stop light circuit from contact 52 to arcuate member 48.

As will also be apparent, the pilot light P functions to indicate to the driver of the vehicle when the direction signal is operating properly. If, for instance, the thermo-responsive wire 62 should break, the contacts of the interrupter switch F will be opened by the spring 88 and the pilot light P will not be illuminated to thereby indicate that the direction signal is not operating as desired. The pilot light P will also function as a reminder to the driver that the direc-

tion signal switch D should be returned to its neutral or off position after completion of the turn or change of direction.

From the foregoing it will be seen that there has been provided both an improved switching means, signal system, and automatic flasher or interrupter switch, and although only a single embodiment has been disclosed herein, various changes and modifications can be made therein without departing from the spirit or scope of my invention as defined in the following claims.

I claim:

1. An intermittently operating switch for signaling systems comprising relatively fixed and movable contacts, a pivoted contact arm for mounting said movable contact for movement toward and away from said fixed contact, an actuating member for said contact arm, said member being pivoted adjacent one end for oscillation and connected to said contact arm adjacent the other end, and means for oscillating said member including a thermo-responsive wire engaging said member intermediate the ends thereof.

2. An intermittently operating switch for signaling systems comprising relatively fixed and movable contacts, means for mounting said movable contact for operation to opposite sides of a dead center position for opening and closing said contacts, a pivotally mounted actuating lever, a spring connected at one end to said means and at the other end to said lever, said lever engaging said spring at a point intermediate the ends thereof whereby on movement of said lever the portion of said spring between said means and said point of engagement may be moved back and forth beyond said dead center to thereby actuate said movable contact in opposite directions.

3. An intermittently operating switch for signaling systems comprising relatively fixed and movable contacts, means for mounting said movable contact for operation to opposite sides of a dead center position for opening and closing said contacts, an actuating lever, a spring connected at one end to said means and at the other end to said lever, said lever having a slot at one end to receive said spring with the arms of said slot engaging opposite sides of said spring at a point intermediate the ends thereof whereby on movement of said lever the portion of said spring between said means and said point of engagement may be moved back and forth beyond said dead center to thereby actuate said movable contact in opposite directions.

4. An intermittently operating switch for signaling systems comprising relatively fixed and movable contacts, a pivoted contact arm for mounting said movable contact for movement toward and away from said fixed contact, an actuating member for said contact arm, said

member being pivoted adjacent one end for oscillation, spring means connecting the opposite end of said member to said contact arm adapted to move said arm with a snap action to open and close said contacts, and means for oscillating said member including a thermo-responsive wire engaging said member intermediate the ends thereof.

5. An intermittently operating switch for signaling systems comprising relatively fixed and movable contacts, a pivoted contact arm for mounting said movable contact for movement toward and away from said fixed contact, an actuating member for said contact arm, said member being pivoted adjacent one end for oscillation and connected to said contact arm adjacent the other end, and means for oscillating said member including a thermo-responsive wire, said wire extending transversely of said member with its ends relatively fixed and adapted to engage said member between its ends and intermediate the pivot of said member and the connection between said member and said contact arm.

25 6. An intermittently operating switch comprising relatively fixed and movable contacts, a pivoted contact arm for mounting said movable contact for movement toward and away from said fixed contact, an oscillating contact lever, a tension spring connected at one end to said contact arm and at the other end to said lever, said lever having a forked end to receive a part of said spring and offset an intermediate portion of said spring to different extents on oscillation of 30 said lever, and means for so mounting said contact arm with reference to said lever that the movement of said intermediate portion of said spring on oscillation of said lever will actuate said contact arm in opposite directions.

40 7. An intermittently operating switch comprising relatively fixed and movable contacts, a pivoted contact arm for mounting said movable contact for movement toward and away from said fixed contact, an oscillating actuating lever 45 for said contact arm, a tension spring connected at one end to said contact arm and at the other end to said lever, said lever being pivoted adjacent one end and having its other end engaging said spring intermediate the ends thereof to offset the intermediate portion of said spring whereby said spring tends to move said lever in one direction about its pivot, means for moving said lever in an opposite direction about its pivot against said spring tension, and means 50 for so mounting said contact arm with reference to said lever that movement of the intermediate portion of said spring by said lever on oscillation thereof will actuate said contact arm in directions opposite to said lever to open and close said contacts.

JOSEPH BELL.
